TYPOGRAPHICAL COMPOSING MACHINE

Henry Harrison Connor, Chicago, Ill., assignor to
Mergenthaler Linotype Company, a corpora-
tion of New York

Application January 12, 1939, Serial No. 250,463

17 Claims. (Cl. 199—28)

This invention relates to typographical composing machines of the general organization represented in Letters Patent of the United States to O. Mergenthaler, No. 436,532 wherein circulating matrices are released from a magazine in the order in which their characters are to appear in print, and then assembled in line, the composed line transferred to the face of a slotted mold, the mold filled with molten metal to form a slug or type bar against the matrices which produce the type characters thereon, and the matrices thereafter returned through a distributing mechanism to the magazine from which they started.

More particularly, the invention relates to that class of machine having a main magazine and an auxiliary magazine mounted in side-by-side relationship, the auxiliary magazine ordinarily containing a matrix font which differs from the matrix font stored in the main magazine.

As the matrices are released from their respective magazines, they drop through channels of an assembler entrance and fall flatwise onto a constantly driven belt, which travels in a horizontal path beneath the channels leading from the auxiliary magazine and thence downwardly in a sloping path beneath the channels leading from the main magazine. As the direction of travel of the matrices released from the auxiliary magazine is changed from a horizontal path to the downwardly sloping path, the matrices strike against and are guided by the lower end of the left partition of the first or rightmost entrance channel leading from the main magazine, and as a result this partition has to be replaced frequently despite the fact that it is made extremely resilient. Such replacement requires considerable time on the part of the operator, and since the machine is out of use during this time, the output of the machine is correspondingly reduced.

In accordance with the present invention, the left partition of the first or rightmost entrance channel leading from the main magazine is made in two parts, one an upper section which is relatively stiff or rigid and fixed in position, and the other a lower section which is flexible or yielding and detachably mounted so that, when necessary, it may be readily and quickly replaced.

For a clear understanding of the invention, reference may be made to the accompanying drawing. In the drawing, however, the invention is shown merely by way of example and in preferred form, and it is obvious that many variations and modifications may be made therein which will still be comprised within its spirit. It is to be

understood, therefore, that the invention is not limited to any specific form or embodiment except insofar as such limitations are specified in the appended claims.

In the drawing:

Fig. 1 is a front elevation showing that portion of the machine with which the present invention is concerned;

Fig. 2 is a vertical section, taken on the line 2—2 of Fig. 1;

Fig. 3 is a perspective view of the modified partition with the lower detachable section separated therefrom;

Fig. 4 is a side view, partly in section, of the modified partition with the lower section attached thereto; and

Fig. 5 is a sectional view taken along the line 5—5 of Fig. 4.

As shown in Fig. 1, the machine is equipped with a main magazine 10 and with an auxiliary 20 magazine 11, the two magazines being arranged side by side or in tandem relation. As the matrices are released from the main magazine 10, they pass into an assembler entrance 9 comprising, as usual, a back plate 17, a series of main 25 matrix guiding partitions 15 secured to said plate in the customary way, and a front or cover plate 16 hinged at the top, as at 16^a, so that it may be swung upwardly from its operative position to give access to the interior parts. In the present 30 instance, the assembler entrance also comprises a reversible throat section 14 (to cooperate with differently channeled magazines) having partitions 14^a which register with the main partition 15 in either position of the throat section. The 35 assembler entrance has an extended or auxiliary portion 9^a of similar construction to receive and guide the matrices released from the auxiliary magazine 11.

After passing through the channels formed by the partitions 15, the matrices drop onto a constantly driven endless conveyor belt 12, whose upper stretch extends horizontally throughout the extent of the auxiliary portion 9^a of the assembler entrance and then slopes downwardly 45 throughout the extent of the main portion of the entrance, as clearly shown in Fig. 1. Overlying the conveyor belt 12 at the point where it changes its direction of travel, there is a leaf spring 13 which serves to prevent the matrices from top- 50 pling over at that point.

As usual, the partition 18 (which constitutes the right wall of the first or rightmost entrance channel leading from the main magazine 10) is heavier than the other partitions 15 and termi- 55

nates a greater distance above the conveyor belt 12, the arrangement being such, that while the partition will stand out of the path of travel of the matrices released from the auxiliary magazine (such as the matrix X in Fig. 1), it will aid in preventing them from toppling over after passing beyond the leaf spring 13. On the other hand, the adjoining entrance partition 19 (which constitutes the left wall of said first or rightmost entrance channel) is arranged in the path of travel of said matrices and must not only absorb the impact of the matrices as they strike against it, but also exert the necessary guiding influence on the matrices to hold them flatwise upon the conveyor belt after their direction of travel has been suddenly changed from a horizontal to a downwardly sloping path.

Heretofore the partition 19, while made thin and flexible enough to perform its necessary functions, has been made in one piece and secured to the back plate 17 in the customary way, with the result that, when it becomes necessary to replace the partition because of wear, breakage or other damage, considerable time and effort is required to effect the replacement, all as well understood in the art.

The present invention overcomes the foregoing objection by making the partition in two sections, one an upper fixed section 19, and the other a lower detachable matrix cooperating section 20. The upper section 19 is heavier than usual, being substantially rigid like the companion partition 18, and is held in place in the customary way, as by means of a rod 19^a passing through a key 19^b projecting rearwardly from the partition and seated in a slot formed in the back plate 17. The lower section 20, however, is highly resilient, comprising in the present instance two thin flexible blades 24 and 25 (preferably made of bronze or some other wear-resistant material), one slightly longer than the other and slightly spread apart at their lower extremities (see Fig. 5).

While the lower section 20 might be independently mounted, it is preferably attached directly to the upper section 19 so as thus to utilize the same means of support (the rod 19^a and the key 19^b) for the two sections. To this end, the upper section 19 is formed at its lower end with a narrow vertical fore-and-aft slot 21, open at the front and lower edges of the section, and with oppositely disposed semi-cylindrical fore-and-aft grooves 22 and 23 opening into the slot; while the two blades 24 and 25, constituting the lower section 20, are formed respectively with opposed semi-cylindrical upset beads 26 and 27 to fit tightly in the grooves 22 and 23.

In attaching the parts, the blades 24 and 25 are placed in face to face contact at their upper ends with the beads 26 and 27 in register and then pushed as a unit rearwardly into the slot 21, the beads entering the grooves 22 and 23. Once attached, the lower section 20 will be held securely in place, being locked against rotational movement by the engagement of that portion of the blades (what may be regarded as a shank portion) with the side walls of the narrow slot 21, and being held against forward displacement by the friction created on the contacting surfaces by the resilience of the blades which tends to separate them. However, the cover plate 16 would be enough in itself to prevent the lower section 20 from becoming detached from the upper section 19. To remove the lower section 20, it is merely necessary to pull it forward out of the slot 21, it being understood that, in effecting

such removal of the lower section when in use, the cover plate 16 is first swung upward out of the way.

While in the present embodiment the invention has been shown as applied only to one particular partition, it is obvious that it might be applied to any other partition which is subject to wear or damage in use.

Having thus described my invention, what I claim is:

1. In or for a typographical composing machine, an assembler entrance partition comprising upper and lower sections, the lower section being detachably supported by the upper section.

2. In or for a typographical composing machine, an assembler entrance partition comprising an upper fixed non-resilient section, and a lower detachable resilient section.

3. In or for a typographical composing machine, an assembler entrance partition comprising an upper fixed non-resilient section, and a lower resilient section detachably supported by the upper section.

4. In or for a typographical composing machine, an assembler entrance partition comprising upper and lower sections, the lower section being removable independently of the upper section and presenting a plurality of resilient matrix guiding blades.

5. In or for a typographical composing machine, an assembler entrance partition terminating at its lower end in a plurality of resilient matrix guiding blades.

6. In or for a typographical composing machine, an assembler entrance partition comprising upper and lower sections, the lower section being supported by the upper section, and said sections being relatively formed to permit the attachment and detachment of the lower section by a relative movement of the two sections.

7. In or for a typographical composing machine, an assembler entrance partition comprising upper and lower sections, said sections being relatively formed to permit the attachment and detachment of the lower section by a fore-and-aft movement of said lower section with respect to the upper section.

8. In or for a typographical composing machine, an assembler entrance partition comprising an upper fixed non-resilient section formed at its lower end with a narrow vertical fore-and-aft slot, open at the front and lower edges of the section, and with fore-and-aft semi-cylindrical grooves opening into the slot, and a lower resilient section presenting a shank portion fitted into said slot and a cylindrical bead fitted into said grooves, whereby the lower section may be attached to or detached from the upper section by a rearward or forward movement of the lower section with respect to the upper section.

9. An assembler entrance partition as defined in claim 8, characterized in that the lower section is constituted by a pair of thin flexible blades arranged in face to face contact at their upper end to provide the shank portion and upset to provide the cylindrical bead.

10. As a new article of manufacture, an assembler entrance partition section formed at its lower end with a narrow vertical fore-and-aft slot, open at the front and lower edges of the section, and with fore-and-aft semi-cylindrical grooves opening into said slot, substantially as shown and described.

11. As a new article of manufacture, an assembler entrance partition section formed at its

- upper end with a substantially cylindrical fore-and-aft bead, to permit its attachment to and detachment from a companion section in its own plane.
5. 12. As a new article of manufacture, an assembler entrance partition section comprising a pair of thin flexible blades each formed at its upper end with a semi-cylindrical upset bead, as and for the purpose described.
10. 13. In or for a typographical composing machine equipped with a main magazine and an auxiliary magazine arranged at the side thereof, an assembler entrance to cooperate with both magazines and presenting a partition which constitutes the left wall of the first or rightmost channel leading from the main magazine and which is arranged in the path of the matrices released from the auxiliary magazine, said partition comprising upper and lower sections, the 15 lower section being removable independently of the upper section.
14. In or for a typographical composing machine equipped with a main magazine and an auxiliary magazine arranged at the side thereof, 20 an assembler entrance to cooperate with both magazines and presenting a partition which constitutes the left wall of the first or rightmost channel leading from the main magazine and which is arranged in the path of the matrices released from the auxiliary magazine, said partition comprising upper and lower sections, the 25 lower section being detachably connected to the upper section.
30. 15. In or for a typographical composing machine equipped with a main magazine and an auxiliary magazine arranged at the side thereof, an assembler entrance to cooperate with both magazines and presenting a partition which constitutes the left wall of the first or rightmost channel leading from the main magazine and which is arranged in the path of the matrices released from the auxiliary magazine, said partition comprising an upper fixed non-resilient section and a lower detachable resilient section.
16. In or for a typographical composing machine equipped with a main magazine and an auxiliary magazine arranged at the side thereof, an assembler entrance to cooperate with both magazines and presenting a partition which constitutes the left wall of the first or rightmost channel leading from the main magazine and which is arranged in the path of the matrices released from the auxiliary magazine, said partition comprising an upper fixed non-resilient section and a lower resilient section detachably connected to the upper section.
17. In or for a typographical composing machine equipped with a main magazine and an auxiliary magazine arranged at the side thereof, an assembler entrance to cooperate with both magazines and presenting a partition which constitutes the left wall of the first or rightmost channel leading from the main magazine and which is arranged in the path of the matrices released from the auxiliary magazine, said entrance partition terminating at its lower end in a plurality of resilient matrix guiding blades.
